E. C. Sanborn
ATTORNEY

UNITED STATES PATENT OFFICE

JOHN FRANK NIEMAN, OF STAMFORD, CONNECTICUT

BUILDING PARTITION OR WALL

Application filed February 10, 1932. Serial No. 591,938.

This invention relates to constructions adapted particularly for building walls, but also for floors, roofs, furring, arches, and so forth, and its principal object is to provide such a construction which is at the same time practical, simple and inexpensive to build, light in weight, and relatively thin, as well as sturdy and durable. Another object is to provide construction of this character which shall be waterproof and capable of constituting exterior walls of buildings. More specifically, an object is to provide a construction embodying a metal frame which is adapted to receive panels of waterproof material attached thereto through water-tight joints and at the same time to support concrete, plaster or the like, applied to said frame and material. Still another object is to make provision in the metal frame of such a wall for reenforcing rods for the concrete plaster or the like. Other objects and advantages of the invention will be apparent from the following detailed description of a preferred embodiment thereof, reference being had to the accompanying drawings, wherein:

Fig. 1 is a front elevation of a supporting frame for a wall in accordance with the present invention.

Fig. 2 is an enlarged horizontal section of a wall construction embodying the frame shown in Fig. 1, as viewed on the line 2—2 of Fig. 1.

Fig. 3 is an enlarged vertical section of the construction shown in Fig. 2, as viewed on the line 3—3 of Fig. 1.

Fig. 4 is a horizontal sectional view through a construction in accordance with the invention, showing one form of employing my improved construction in connection with a vertical I-beam or the like.

Fig. 5 is a vertical section illustrating one manner of employing my improved construction in connection with a horizontal I-beam or the like.

Fig. 6 is a vertical section showing a manner of employing my construction for a roof.

In the drawings, there is shown at 5 a metal frame comprising generally horizon-

tal ribs 6 and generally vertical ribs 7, intersecting as at 8 so as to form rectangular openings 9 between the ribs. As shown, each of these ribs preferably extends the full length or height of the frame and is considerably wider than it is thick. Flanges 10 are shown formed integral with the ribs 6 and 7 and extending at right angles thereto, these flanges preferably being continuous around the sides of the rectangular openings 9 and lying in one plane. Said flanges preferably intersect the ribs between their edges as shown in Figs. 2 and 3, but if desired may extend across the edges of the flanges. The whole frame, comprising the ribs 5 and 6 and the flanges 10, is desirably made of a single piece of metal which may be stamped out or otherwise formed.

In order to form a water-tight wall, panels 11 of water-proof material, such as glass, are shown secured between the ribs 6 and 7 through suitable plastic material 12, for example, putty. The panels 11 are desirably only slightly smaller than the space between the ribs 6 and 7, and at the same time larger than openings bounded by the flanges 10, so as to overlie the latter, while the putty or the like is applied along all the edges of the panels, thus resulting in a complete seal between the panels and the frame. The ribs 6 and 7 and the flanges 10 thus form, in combination with the sealing material, a firm support for the panels 11, and at the same time these ribs are reenforced by the flanges.

Plaster, concrete, stucco material, or the like is shown applied as at 13, to the frame construction after the panels 11 have been secured in place, and preferably at both sides of the frame, so that the latter is substantially embedded in the material. The frame 5 thus reenforces the wall and at the same time the ribs 6 and 7 serve as bonds for the concrete or the like. If additional support is required for the latter, however, horizontal reenforcing rods or wires 14 may be extended through the ribs 7, the frame 5 thus serving to carry the wires. Although no vertical rods are shown or generally required, it will be understood that they may be similarly applied to the frame, if desired.

The present invention thus provides a wall construction which is not only self-supporting but which is also very sturdy and capable of supporting considerable roof loads or the like. At the same time it is capable of being simply and rapidly erected. Moreover, it is waterproof and hence avoids the necessity for repairs sometimes required to stop leaks in the usual brick or other wall constructions, particularly exterior walls.

In order to anchor the frame in a foundation or other part of a building, the frame 5 may have projections 15 formed at its outer sides, though other convenient securing means may be employed.

While the openings 9 have been described as rectangular, it will be apparent that the shape of the same may be varied. A single frame 5 may advantageously be employed for a given wall, being formed in the proper size. However, several frames may, if desired, be joined together in any convenient manner, as for instance, by welding, bolting or riveting.

Referring to Fig. 4, there is shown at 20 an I-beam having secured thereto in any suitable fashion an angle iron 21. This angle iron may be secured to and serve to support their ribs 7 of frames 5, preferably of the character shown in Fig. 1. Where two such frames are to be joined, adjacent ribs 7 may have a thin layer of waterproof cement or the like interposed therebetween as shown at 22. Any convenient means (not shown) may be employed for securing the ribs 7 to the angle iron 21. If desired, the I-beam 20 may be embedded in concrete or the like, and for additionally reinforcing the concrete frame members 23 and 24, carrying rods 14 may be employed. The members 24 are shown as consisting of intersecting vertical ribs 7', this construction being particularly suited to forming corners of buildings. The members 23 and 24 may be formed in a single frame, and have projections or flanges 10 for cooperating with waterproof parts 11, in the manner already described. Where this construction is employed at the corner of a building, other frames 5 may be secured to the members 23 in the manner already described, and these other frames 5 may extend at any desired angle to the members 23.

In Fig. 5, there is shown an I-beam 25, frames 5 being provided with flanges 15' for seating on the top of the I-beam. Rods 14 may have extensions 14' of any desired configuration. The other ends of frames 5 (not shown) may rest on other I-beams in a similar manner, thus providing a simple and light floor construction.

In Fig. 6 there is shown an I-beam 26 serving as the ridge pole of a roof and secured to an I-beam 27 serving to support one side of a sloping roof which is shown constructed in accordance with the present invention. In this view, the frame 5, only one panel 7" of

which is shown, has flanges 10' adapted to rest on the beam 27, and to receive waterproof partitions 11. The ends of partitions 11 at the top of the roof may be embedded in putty 12 cooperating with an inverted T member 28 carried by the beam 26. This member 28 may be provided with an opening, as shown, for receiving the ends of reinforcing rods 14. Concrete, stucco, or the like, as shown at 13, may be applied as finishing and fire-proofing material.

It will thus be apparent that my construction is particularly advantageous in that it is adaptable to many varied requirements of building construction work. At the same time, it is extremely simple, and capable of being rapidly erected, resulting in a substantially water-tight, sound-proof, and fire-proof construction. Moreover, it is extremely light in weight and relatively thin as compared to ordinary brick or concrete constructions. For instance, the thickness of wall required in my present construction in order to meet the various requirements of a good building wall, is only about one-half to three-quarters of the thickness of customary constructions at present in use. In this manner, a considerable saving in weight may be effected, with the result that taller buildings may be built without increasing the load imposed on foundations, or on the other hand, the required foundations for a given building may be reduced, thus effecting a considerable saving, and lightening the weight of the building throughout.

While the construction has been illustrated in conjunction with steel I-beams, it will be understood that my construction is capable of being employed with other types of buildings and also with other types of steel construction. Moreover, while cement, concrete, stucco, and the like, have been suggested as material for present purposes, other types of material may be employed. For instance, terra cotta tiles or veneer tiles might be employed, possibly on the outside of a thin layer of concrete, or the like.

The terms and expressions which have been employed are used as terms of description and not of limitation, and there is no intention, in the use of such terms and expressions, of excluding any equivalents of the features shown and described, or portions thereof, but it is recognized that various modifications are possible within the scope of the invention claimed.

I claim:

1. In the construction of walls, partitions, floors, ceilings, roofs or the like, a metal frame having intersecting ribs forming openings therebetween, flanges extending from said ribs and surrounding said openings, panels of water-proof material, means to secure the panels between the ribs and overlying the flanges, and material such as stucco.

applied to the frame and panels at both sides thereof, whereby the frame is substantially entirely embedded in the material.

2. In the construction of walls, partitions, floors, ceilings, roofs or the like, a metal frame having intersecting ribs forming openings therebetween, flanges extending from said ribs and surrounding said openings, said ribs and flanges being formed integral, panels of water-proof material, means to secure the panels between the ribs and overlying the flanges, and material such as stucco applied to the frame and panels at both sides thereof, whereby the frame is substantially entirely embedded in the material.

3. In the construction of walls, partitions, floors, ceilings, roofs or the like, a metal frame having intersecting ribs of greater width than thickness, said ribs forming openings therebetween, flanges extending generally at right angles to said ribs and between their edges, said flanges being continuous around said openings and said ribs and flanges being formed integral, panels of waterproof material, means to secure the panels between the ribs and overlying the flanges, and material such as stucco applied to the frame.

4. In the construction of walls, partitions, floors, ceilings, roofs or the like, a metal frame having intersecting ribs forming openings therebetween, flanges extending generally at right angles to said ribs, said flanges being continuous around said openings and said ribs and flanges being formed integral, openings in some of said ribs for receiving reinforcing rods, panels of waterproof material, means to secure the panels between the ribs and overlying the flanges, and plastic material applied to said frame.

40 5. In the construction of walls, partitions, floors, ceilings, roofs and the like, a unitary metal frame having intersecting ribs extending at angles to one another and forming openings therebetween, flanges extending from said ribs and surrounding said openings, reinforcing rods extending through apertures formed in said ribs, said apertures being surrounded by the metal of the ribs, panels of material maintained between the ribs and overlying the flanges, and coating material applied to said frame and panels.

6. In the construction of walls, partitions, floors, ceilings, roofs and the like, a unitary metal frame having intersecting ribs extending at angles to one another and forming openings therebetween, continuous flanges extending from said ribs and surrounding each of said openings, said ribs and said flanges being joined in a waterproof manner, apertures formed in said ribs and surrounded by the metal thereof, reinforcing rods extending through said apertures, and panels of water-proof material maintained between said ribs and overlying said flanges and in water-tight engagement therewith, and coat-

ing material overlying at least one side of said frame.

7. In the construction of walls, partitions, floors, ceilings, roofs and the like, a unitary metal frame having intersecting ribs forming openings therebetween, flanges extending from said ribs and surrounding said openings, panels of water-proof material, means to secure the panels between the ribs and over-lying the flanges in a water-proof manner, and material such as stucco applied to the frame and panels.

8. In the construction of walls, partitions, floors, ceilings, roofs and the like, a unitary metal frame having intersecting ribs forming openings therebetween, flanges extending from said ribs between opposite edges thereof, apertures formed in said ribs at either side of said flanges, reinforcing rods extending through said apertures at either side of said ribs and being surrounded by the material of the ribs, panels of sheet material carried by said flanges, and coating material substantially covering the frame.

9. In the construction of walls, partitions, floors, ceilings, roofs and the like, a unitary metal frame having intersecting ribs forming openings therebetween, flanges extending from said ribs between opposite edges thereof, apertures formed in said ribs at least at one side of said flanges, reinforcing rods extending through said apertures and being surrounded by the material of the ribs and engaged with said frame whereby a unitary construction is provided, panels of sheet material adapted to overlie said flanges, and coating material substantially covering the frame.

10. In a construction for walls, partitions, floors, roofs and the like, a unitary metal frame having intersecting ribs forming openings therebetween, flanges extending from said ribs at opposite sides of said openings and between the opposite edges of the flanges, apertures formed in said ribs and surrounded by the material thereof for receiving and supporting reinforcing rods, the frame and rods forming a marketable unit, panels of water-proof material operatively secured between the ribs and overlapping the flanges, and coating material such as a cement composition applied over both sides of the metal frame and covering the metal, whereby a monolithic reinforced concrete slab of required strength, less thickness and less weight is produced, which slab conforms to recognized requirements for fire-proof construction.

In testimony whereof, I have signed my name to this specification this 8th day of February, 1932.

JOHN FRANK NIEMAN.
